UNITED STATES PATENT OFFICE.

JOHN P. NISSEN, OF PHILADELPHIA, PENNSYLVANIA.

DESIGN FOR A STOCKING.

Application filed June 5, 1925. Serial No. 13,666. Term of patent 14 years.

To all whom it may concern:

Be it known that I, JOHN P. NISSEN, a citizen of the United States, residing at Philadelphia, in the county of Philadelphia and State of Pennsylvania, have invented a new, original, and ornamental Design for Stocking, of which the following is a specification, reference being had to the accompanying drawing, forming a part thereof, in which—

Figure 1 is a view in elevation of a stocking showing my new design,

Figure 2 is a similar view but with the top reversed.

The essential feature of my design is a leg portion having an ornamental ring adjacent the knee and tapering from the rear forwardly on both sides to the front in series of corresponding steps.

I claim:

The ornamental design for a stocking, as shown.

JOHN P. NISSEN.
